UNITED STATES PATENT OFFICE.

CLARENCE A. BERKINS, OF MINNEAPOLIS, MINNESOTA.

HYDROCARBON BURNER.

Application filed October 17, 1921. Serial No. 503,060.

To all whom it may concern:

Be it known that I, CLARENCE A. BERKINS, a citizen of the United States, residing at Minneapolis, in the county of Hennepin and State of Minnesota, have invented certain new and useful Improvements in Hydrocarbon Burners; and I do hereby declare the following to be a full, clear, and exact description of the invention, such as will 5 enable others skilled in the art to which it appertains to make and use the same.

My present invention relates to hydrocarbon burners adapted for general use in furnaces, boilers, stoves and the like, and 15 has for its object to simplify the same and to improve the operation thereof.

Generally stated, the invention consists of the novel construction and combinations of parts hereinafter described and defined in 20 the claims.

The burner designed as illustrated in the accompanying drawings, has been especially designed for use in heaters, boilers, or furnaces of domestic heating plants, but may 25 be made in various different sizes and applied generally for the burning of heavy hydrocarbon liquids. A crude oil product, known as distillate and which is of considerably lower grade than kerosene, is ad- 30 visably used, but lighter or heavier hydrocarbon oils may be used.

As preferably designed, the burner is a duplex or twin burner having two generating nozzles.

35 In the accompanying drawings, which illustrate the invention in its preferred commercial form, like characters indicate like parts throughout the several views.

Referring to the drawings:

40 Fig. 1 is a perspective with some parts broken away, showing a heater such as a hot water heater or steam boiler in outline and showing the improved burner applied therein;

45 Fig. 2 is a vertical longitudinal section taken centrally through the improved burner; and

50 Fig. 3 is a plan view showing the air base or box of the burner and its generating nozzles, but with the dome removed.

55 Of the parts of the heater, the numeral 4 indicates the body shell, the numeral 5 the grates and the numeral 6 the ash pit door opening, from which latter the doors may be removed.

The complete burner, as preferably con-

structed, comprises a hollow casting air base or box 7 of oblong form, open at its bottom but closed at its top, except for a large central air intake port 8 that is preferably approximately rectangular in form. On each side of the air port 8, the top plate of the base 7 is formed with depressed basins 9, from the centers of which rise upwardly tapered conical generating cones or nozzles 10, the exterior conical surfaces of which are stepped or formed in different altitudes with annular ledges 11 that progressively increase the external diameter of the cones and perform an important function presently to be noted. Said cones 10, for another important reason, are made hollow and tapered and, at their apexes or uppermost portions, they are tapped by small fuel supply pipes 12 that have contact with the cones 75 only at their upper ends where they connect to said cones.

The fuel supply pipes 12 are extended downward and thence outward through the fuel door opening 6 and are connected to a 80 common fuel supply pipe 13 that leads from a suitable source of fluid fuel supply. The branch pipes 12 are shown as provided with independently operative globe valves 14 and with normally open cut-off valves 15, the 85 latter of which are provided with projecting arms 16 to which weight-acting buckets 17 are attached.

Below their upper portions but above 90 their bottoms, the basins 9 are tapped by small overflow pipes 18 that lead downward and outward through the door opening 6 and terminate in position to be discharged into the respective buckets 17. For the purposes of this case, it is only necessary to 95 state that if the flame from the burner should go out and the oil continue to flow thereto, the oil overflowing through a pipe 18 would run into a bucket 17, increasing the weight thereof to an extent that would 100 close the co-operating cut-off valve 15.

The base 7 is intended to rest upon the grates 5 and the grates should be closed, surrounding the base by ashes or any other suitable means so that all of the air passing 105 into the five box of the heater will have to pass upward through a central port 8.

The generating cones or nozzles 10 are concentrically located within the down-turned air tubes 19 of a bifurcated air dome 110 20 that is formed between said air tubes with a large depending air intake stack 21.

This air intake stack 21 is spaced from the exterior of the air tubes 19 so that the planes can lap or project entirely around said tubes. Moreover, this air intake stack, at least in 5 its lower portion, is made approximately rectangular so as to fit the large intake port 8 of the base 7 and is extended down into and through the top plate of said base. This causes the air tubes 9 always to assume 10 proper positions around the generating cones. It is important to note that the lower ends of the air tubes 19 are concentric with but terminate above the basins 9, thereby leaving air passages. This dome structure is 15 adapted to be gravity-held in working position.

In the operation of the burner, the oil will be delivered upward through the branch pipes 12 and will flow at the apexes 20 of the generating cones 10. Inasmuch as the cones are spaced from the pipes 12, the oil will not be heated to any considerable extent and, hence, will not be carbonized within said pipes. When the burner is in action, 25 the cone and especially the depending air tubes 19, and also the generating cones 10 and basins 9, will be heated to a high degree of temperature, sometimes becoming nearly or quite red hot. Hence, when the 30 oil overflows at the upper ends of the generating cones, it will trickle or run down the same and, because of the increasing diameter of the cones, will be spread thinner and thinner so that, under the action of intense heat, 35 it will be almost instantaneously vaporized and taken up by and thoroughly commingled with the air, thereby quickly forming with the air the proper mixture for supporting complete combustion, resulting 40 in the hottest kind of a flame and the formation of little or no carbon. The steps or ledges on the exteriors of the cones further retards the speed of downward travel or flow of the oil and hence, gives the air a 45 better chance to absorb the same, so that when the burner is in proper action no oil will reach the basins 9. The mixture will ignite and the flames will start within the depending tubes 19 and will be deflected 50 outward and upward by the then hot basins, so that there will be produced substantially 55 annular upwardly flaring flames of great intensity.

When heavy oils or hydrocarbons are used, it is advisable to start the burner into action by using a small priming of gasoline, which may be poured into the basins 9 and ignited.

If, for any reason, the flame of one of 60 the burners should go out, the oil will con-

tinue to flow until it fills the basin 9 to the altitude where the oil will run out through the overflow pipe 18. With the arrangement shown, said pipe 18 will direct the overflowing oil into one of the pails 17 65 and, before the pail becomes filled, its weight will be such that it will move its lever 16 down and close the co-operating cut-off valve 15, thereby stopping the further flow of oil to that side of the burner. 70

By means of the valves 14, the flow of oil to the sides of the burner may be independently regulated and, of course, the main supply pipe 13 may be provided with a valve for simultaneously cutting off the supply to both sides of the burner. In actual practice, this burner has been found highly efficient for the purposes had in view. It affords very complete combustion and can be economically operated. Moreover, the 75 burner is of very simple construction, having no parts that can easily get out of order and, moreover, may be made at comparatively small cost, since the burner proper involves only two castings, to wit: the 80 base and the dome members. 85

What I claim is:

1. A burner comprising a base adapted to rest upon a grate and having a large angular centrally located opening and, on opposite sides of said opening, annular basins and cones rising from said basins, in combination with a dome structure having a large centrally located angular intake stack detachably seated in said angular air passage between said basins and to be held against rotation, said dome having outwardly and downwardly extended air tubes that concentrically surround said cones and terminate above said basins. 95

2. The structure defined in claim 1 in further combination with fuel intake tubes leading upward through said cones to the upper ends thereof, and overflow tubes leading from said basins. 100

3. A device of the character described comprising a base adapted to rest upon a grate and having an angular opening therein, a burner laterally offset with respect to said opening and provided with an annular basin and a co-operating cone rising from said basin, in combination with a dome structure having an angular intake stack detachably seated in said angular opening and having a downwardly extended air tube 110 that concentrically surrounds said cone and terminates above said basin. 115

In testimony whereof I affix my signature.

CLARENCE A. BERKINS.
